GAS-SUPPLY-CONTROLLING MEANS.

1,079,416.

Specification of Letters Patent. Patented Nov. 25, 1913.

Application filed March 15, 1912. Serial No. 684,030.

To all whom it may concern:

Be it known that I, LEO A. KORB, a citizen of the United States, and residing at Richwood, Nicholas county, State of West Virginia, have invented certain new and useful Gas-Supply-Controlling Means; and I do declare the following to be a clear, full, and exact description of the invention, attention being called to the drawing which accompanies this application and forms a part thereof.

Hot-water for domestic purposes is generally obtained by means of heaters connected with the water-supply, (service branch), in a manner that water drawn off for use is caused to pass through such a heater so that it becomes hot during this passage. In most cases gas is the fuel used in these heaters, it being applied by means of suitable burners. Devices have been provided whereby the gas-supply to these burners is automatically controlled in a manner that gas is furnished only when water is taken and passes through the heater, the gas-supply at all other times being cut off. Whenever water is taken these devices are rendered active by the flow of the water and are caused by means of suitable intermediate connections to actuate in a proper manner a valve which controls the flow of gas through the pipe whereby the burners are supplied. My invention relates to such water-actuated means and devices for automatically controlling the gas-supply to a heater-burner and consists of the particular construction of these means and devices as hereinafter described and claimed and as illustrated in the accompanying drawing, in which:—

Figure 1, shows an elevation of the means and devices contemplated by my invention. Fig. 2, shows a vertical section of the same in inactive position. Fig. 3, shows in a similar view the parts in operative position.

In the drawing, 6 indicates a pipe which serves to supply gas to the burners of a water-heater of customary type and not shown. Flow of gas through this pipe is controlled by a cylindrical piston-valve *a*, contained in a chamber formed by a housing A, inserted in pipe 6, so as to form a connected part thereof. This valve-chamber is divided by a partition 7 which has a circular opening around which the valve seat 8 is formed. The valve is fitted to slide in this opening and with its head 9 to and from

seat 8. When the valve moves from its closed position shown in Fig. 2, into open position shown in Fig. 3, the gas passes through port-holes 11, which are arranged in an inclined line, starting from the head of 60 the valve inwardly and whereby the gas is admitted to the burners in a gradually increasing flow which reaches its normal maximum when the valve has moved farthest away from its seat and when all its port-holes are uncovered. The gas is gradually cut off in a similar manner when the valve moves back into closing position.

As before explained gas is used only at intervals to heat cold water in proportion to 70 the quantity of water drawn off from time to time which withdrawal causes a flow of water through the heater and through the pipes connected thereto. The motion of this flowing water is utilized to actuate the device referred to before and whereby the valve controlling the gas-supply is automatically operated in a manner that as soon as water commences to flow through the heater and the connected pipes, this valve 80 opens and admits gas to the burners, the gas being immediately cut off again as soon as the water ceases to flow. A pilot-flame from a small burner, not subject to control by this gas-valve, serves to ignite the gas whenever 85 admitted to the burners. This water-actuated device consists substantially of a hollow piston *b*, contained in a housing B and which housing is inserted in a water-pipe 12, it being provided with nipples 13 for connection by means of couplings 14 (Fig. 1). This pipe forms a communicating part of the water-heater-circulation and of the hot-water-pipe leading to the places of consumption, so that, whenever water is drawn causing 90 a flow through the heater, the water in pipe 12 commences also to flow and passes through housing B.

15 is the inlet to this housing and 16 is the outlet therefrom, the latter being below the former; and between the two there is an annular lip 17 against which the lower part 18 of piston *b* is fitted. The face of the lip is grooved and adapted to hold water which provides a packing sufficiently close for the 105 purpose.

The upper part 19 of piston *b* is of reduced diameter and fitted into the outwardly open neck 21 of the housing, said neck being arranged to form a stuffing box 110

of which 22 is the gland whereby packing 23 is held in place. Passage of water through the hollow piston is rendered possible by inlet-ports 24 in its upper part and by outlet ports 25 in its lower part, which latter are arranged in a line ascending from the lower end of the piston and analogous to the ports in the gas-valve.

The normal position of the parts is shown 10 in Fig. 2, and in which lip 17 prevents passage of water through the piston and thereby communication between inlet 15 and outlet 16 of housing B. The interior of the piston is always open to inlet 15 through 15 ports 24. If now water is drawn from any of the outlets in communication with pipe 12, the diminishing pressure below and outside of the piston causes the same to yield to the higher pressure above and inside of 20 it. Thereupon the piston descends until all of its outlet ports 25 are gradually uncovered as shown in Fig. 3, permitting free flow of water through it. The piston is connected to gas-valve *a* by a rod 26, so that its 25 movements are communicated to the gas-valve and cause the same to open likewise. 27 is a by-pass through which the lower part of housing B outside of the piston communicates directly with inlet 15 and independent of control by this piston. As soon as closing of the open outlet causes flow of 30 water through pipe 12 to cease, the pressure below and outside of the piston rises again by reason of inflow through by-pass 27. The 35 piston is thereby forced upwardly until passage through its ports 25 is closed as they pass gradually above lip 17, after which the piston stops in the balanced position shown in Fig. 2. This movement at the same time 40 closes the gas-valve.

28 is a valve whereby passage through by-pass 27 may be regulated to the proper degree.

The two housings A and B are connected 45 by a yoke 29.

It will be observed that the valve which controls the supply of the gas is subject to positive movement by the piston as obtained by the flow of water and the use of springs 50 is entirely dispensed with.

Having described my invention, I claim as new:

1. In means for controlling the gas-supply to a heater-burner by means of a water-actuated device, the combination of a gas-supply-pipe, a valve controlling passage therethrough, a cylindrical piston-housing open at one end and provided with an inlet and an outlet opening in its side, a water-pipe in 60 communication with these openings, a hol-

low cylindrical piston closed at both ends movably fitted to this housing and having part of it concentrically contracted, which contracted part extends outwardly through the open end of the housing, a stuffing-box 65 in the piston-housing fitted to this contracted part of the valve, inlet ports in the side of the contracted part of the piston, outlet ports in the side of its wider part and a rod whereby the piston is connected to the 70 valve in the gas-supply-pipe.

2. In means for controlling the gas-supply to a heater burner by means of a water-actuated device, the combination of a cylindrical piston-housing having between its 75 ends an annular inwardly projecting lip and being open at one end where an outwardly extended neck is provided, diametrically opposite openings in this housing, one above and one below the lip mentioned, serving respectively for admission and for egress of water, a cylindrical, hollow piston closed at both ends and fitted to contact with the lip mentioned and also into the neck of the housing, vertically spaced ports in 85 the side of the piston to permit water to enter the same and to pass out therefrom, a gas-supply pipe, a valve which controls passage through the same and means to connect this valve and the piston so that both move 90 together.

3. In means for controlling the gas-supply to a heater-burner by a water-actuated device, the combination of a hollow, cylindrical valve which controls the flow of gas 95 and a cylindrical, hollow piston which controls the flow of water, a rod whereby both are rigidly connected in axial alignment, ports to admit water to the hollow piston, additional ports which form outlets for the 100 water from the piston, ports to permit passage of gas through the valve mentioned, a housing for this valve, a housing for the piston provided with an annular lip to which the piston is fitted and in which housing said 105 piston occupies a normal position with the outlet ports above this lip, an inlet for water to the housing above this lip, and an outlet for water below the same, the outlet ports in the piston and the ports in the valve being 110 arranged in a line inclined to the axis of both so that upon movement a proportionally graduated passage of respectively water and gas takes place.

In testimony whereof, I hereunto affix my 115 signature in the presence of two witnesses.

LEO A. KORB.
